UNITED STATES PATENT OFFICE.

LUCIEN A. DEXTER, OF GRAND RAPIDS, MICHIGAN, ASSIGNOR TO NATIONAL BRASS COMPANY, OF GRAND RAPIDS, MICHIGAN, A CORPORATION OF MICHIGAN.

LATCH CONSTRUCTION.

Application filed February 9, 1922. Serial No. 535,217.

To all whom it may concern:

Be it known that I, LUCIEN A. DEXTER, a citizen of the United States of America, residing at Grand Rapids, in the county of 5 Kent and State of Michigan, have invented certain new and useful Improvements in Latch Construction; and I do hereby declare the following to be a full, clear, and exact description of the invention, such as will 10 enable others skilled in the art to which it appertains to make and use the same.

This invention is concerned with latches, particularly latches of the type shown in United States Patent No. 1,327,695, issued 15 Jan. 13, 1920, and which are adapted to be installed on swinging doors, and in which the entire latch structure, substantially, is housed within a cylindrical housing which may be installed in connection with a door 20 by merely boring the proper openings for the housing and the operating member for the latch mechanism. In latches of this type, the latch bolt head normally projecting from the outer end of the housing 25 should be properly guided at opposite sides so that it will not tilt or otherwise change position as it is pressed against in closing a door equipped with the latch, and the present invention has the ready and economical 30 production of such guiding means as its primary object and purpose. A further object of the invention is to provide the guiding means in a very simple and economical manner, striking oppositely positioned 35 guides from two separate members located at the outer end of the latch housing and connected thereto, through which openings have to be made for the passage of the latch bolt head, the metal being cut from 40 said members to make the openings required and turned inwardly into the latch housing in position for the bolt head to pass freely between, serving as substantially rigid guides for the bolt head and holding 45 it from tilting or other undesired movements. These and many other objects and purposes, together with novel constructions for attaining the same, will appear as understanding of the invention is had from 50 the following description, taken in connection with the accompanying drawing, in which,

Fig. 1 is a fragmentary longitudinal section taken vertically at the outer end of the 55 latch.

Fig. 2 is a rear perspective view of the outer end face plate connected at the end of the latch housing.

Fig. 3 is a perspective view of the sheet metal cap which is permanently attached 60 to said plate.

Fig. 4 is a section through the connected cap and plate taken on the plane of line 4-4, of Fig. 5.

Fig. 5 is a similar section taken on the 65 plane of line 5-5, of Fig. 4, and

Fig. 6 is a rear elevation of the connected cap and plate, parts of the plate, at the ends, being broken away.

Like reference characters refer to like 70 parts in the different figures of the drawing.

In the construction of the latch, a cylindrical housing 1 is used within which the latch mechanism is received, said mechanism including a member 2 of metal at the 75 front end of which an end 3 is turned substantially at right angles to lie across and within the housing. A latch bolt comprising a rod 4 with a head 5 at its outer end is connected with the end 3, having a slideable 80 connection therewith which is fully shown and described in the patent above noted, the rod and head being normally projected outwardly by a spring 6 around the rod between head 5 and the end 3, as shown. 85

A cap 7 of sheet metal covers the open outer end of the housing 1 and is attached thereto by means of projections 8 pressed outwardly from the sides of the housing to enter suitable bayonet slots in the sides of 90 the cap (not shown), which are no part of the present invention. A face plate 9 is located against the outer end of the cap and permanently secured thereto, as will later appear. 95

The head 5 must pass through the outer end of the cap, and in making the opening to permit such passage, a tongue of metal 10 is struck from the cap end and turned inwardly, as shown, an opening 11 being 100 made. Additional pieces of metal are cut from the end of the cap to leave a recess 12 directly opposite the tongue 10, and two recesses 13 opposite each other and at right angles to the recess 12 and the tongue 10. 105

The plate 9 also has an opening 14 for the passage of head 5 and in making the same the metal is struck back so as to make a relatively large tongue 15 at one side of the opening and two oppositely smaller 110

tongues 16 at other sides of the opening which are at right angles to the side at which tongue 15 is located. Tongues 16 are of a width that the same substantially fill the recesses 13, passing therethrough and then being bent over against the inner side of the end of the cap to make a permanent connection between the cap and plate 9, as best shown in Fig. 4.

10 When thus attached and with the cap placed over the end of the housing 1, tongues 10 and 15 extend into the housing, one at each side of the openings through the plate and cap, are in parallel relation to each 15 other and one at each side of the head 5, serving as guides therefor. The guide tongue 15 is at the longer flat side of the head, and guide tongue 10 at the opposite shorter flat side, at which side the head is 20 bevelled to make a cam surface to ride against the strike on the door casing in closing, the head and attached bolt rod 4 moving inwardly and spring 6 being compressed. The pressure acting against said 25 cam side has a tendency to tilt the head and rod to one side, being stopped, however, by the tongue 15. As the head is pressed inwardly, its other side rides against the guide 10 and it cannot move or tilt in the opposite 30 direction. The head is firmly held and guided so that it must move directly in or out, neither the pressure of the spring or against the inclined side of the head having any tilting effect which is not obviated 35 by the guides. The construction is very simple, practical and effective in every way and in practice has proved particularly satisfactory.

I claim:

- 40 1. In a latch construction, a face plate having an opening therethrough and formed with a tongue extending to the rear at one side of the opening, a cap attached to the rear side of the face plate, its end contacting with the plate having an opening therethrough and formed with a tongue extending to the rear, said openings in the plate and cap being in conjunction and said tongues being spaced apart and substantially parallel to each other and extending in the same direction from opposite sides of the openings, a latch housing connected with the cap and a latch bolt in the housing having a head guided between the two tongues, substantially as described.
- 45 2. In a latch construction, a face plate having an opening therethrough, a cap of sheet metal located against the rear side of

the plate and likewise having an opening therethrough in conjunction with the opening in the plate, means permanently connecting the plate and cap together, and a tongue struck from both the plate and cap extending to the rear into said cap, said tongues extending at opposite sides of the 65 openings and being located in parallel relation to each other.

3. In a latch construction, a cylindrical housing, a latch bolt having a head mounted therein, a sheet metal cap having an opening therethrough for the passage of the head of the bolt attached at one end of the housing, a guide on said cap extending into the housing at one side of the head of the bolt, a face plate secured to the cap also having an opening therethrough, and a second guide on the face plate extending through the opening in the cap at the opposite side of the head of said bolt, substantially as described.

4. In a latch construction, a cylindrical housing of sheet metal, a latch bolt mounted for longitudinal movements within the housing, said bolt having a head at its outer end, a closure formed of a single piece of sheet metal for the outer end of the housing having an opening to pass the head of the bolt therethrough, and two oppositely located guides attached to the closure one of said guides being integrally formed with the closure, and extending into the housing between which the bolt head is guided and held in its movements.

5. In a latch construction, a housing having an open outer end, a cap located over said end of the housing and having an opening therethrough, the metal in cutting said opening being turned into the cap and housing rearwardly to provide a tongue, a plate secured to the cap, said plate also having an opening cut therethrough with the metal severed in cutting said opening turned to the rear through the opening in the cap at one side thereof directly opposite the position of the tongue cut from the cap, said metal turned to the rear from the plate providing a second tongue paralleling the first tongue, and latch mechanism mounted in the housing for movement lengthwise thereof, said mechanism including a latch bolt having a head at its outer end guided between said tongues in the movements thereof, substantially as described.

In testimony whereof I affix my signature.

LUCIEN A. DEXTER.
